UNITED STATES PATENT OFFICE.

WILLIAM D. JANES, OF SAGINAW, MICHIGAN.

PAWL FOR SHADE-ROLLERS.

SPECIFICATION forming part of Letters Patent No. 781,655, dated February 7, 1905.

Application filed October 20, 1904. Serial No. 229,826.

To all whom it may concern:

Be it known that I, WILLIAM D. JANES, a citizen of the United States, residing at Saginaw, in the county of Saginaw and State of Michigan, have invented certain new and useful Improvements in Pawls for Shade-Rollers; and I do hereby declare the following to be a full, clear, and exact description of the invention, such as will enable others skilled in the art to which it appertains to make and use the same.

This invention relates to shade-rollers, and pertains more particularly to certain constructions and arrangements in the pawl-plate or cap of a shade-roller whereby the pawls may be held back out of contact with the notched spear of the roller, thereby rendering the pawls inoperative.

As is well known, shade-rollers designed to operate with downwardly-hanging shades are provided with pawls in the shade-roller cap to lock the roller at any desired position. On the other hand, when the shade-roller is mounted at the bottom of the window and carries an upwardly-moving shade action of the shade-roller pawls is not desired.

It is the object of my present improvement to provide means by which the pawls can be rendered inoperative, and thereby make the roller suitable for use at the bottom of the window and adapt it to operate an upwardly-moving shade.

My improvement is shown in the accompanying drawings, in which—

Figure 1 is an enlarged face view of a shade-roller cap embodying my improvement. Fig. 2 is a similar view broken away in part; and Fig. 3 is a transverse section taken on the line *w-w* of Fig. 2, the outer plate of the shade-roller cap being removed.

1 is the outer plate of the shade-roller cap, and 2 is the inner plate.

3 is the shade-roller spear that projects through the openings in the two plates.

Between the outer and inner plates are the usual pivotally-mounted pawls 4 and 4^a, adapted to engage the spear 3. As heretofore constructed these pawls are free to move back and forth as the cap revolves with the roller, and no means is provided for locking the pawls back to prevent their engaging with the spear, as above noted. In my present device I provide holes 1^a and 1^b in the outer plate 1, so located as to register with the notches 4^b of the pawls 4 and 4^a when the latter are drawn back out of engagement with the spear 3. In the inner plate 2 I provide corresponding holes 2^a and 2^b. These holes are preferably rectangular in form and are made by punching down the metal of the plate 2, so as to form a downwardly-projecting flange 2^c. These flanges when driven into the end of the shade-roller lock the inner plate 2 in position on the end of the roller. The holes 1^a and 2^a and 1^b and 2^b, respectively, register with each other, so that a small pin, the end of a match, or other suitable stop may be passed through them after the pawl has been moved back to the position shown by dotted lines in Fig. 1, which effectually prevents the pawl from engaging the spear.

What I claim as my invention, and desire to secure by Letters Patent, is as follows:

In a shade-roller cap, the combination with the pivotally-mounted pawl having a notch, of an inner and an outer plate, each having a perforation registering with the notch of said pawl when the pawl is drawn back.

In testimony whereof I affix my signature in presence of two witnesses.

WILLIAM D. JANES.
